PIPE AND NUT WRENCH

John W. Beery, Rosamond, Calif.

Application March 30, 1931. Serial No. 526,151

1 Claim. (Cl. 81—91)

This invention relates to improvements in combination pipe and nut wrenches and the like.

One of the objects of this invention is to provide a simple, efficient and inexpensive pipe and nut wrench designed and constructed in such a manner that two jaw heads may be swung to adjustably grip a nut or a pipe, the arrangement of parts facilitating this operation.

Another object of this invention is to provide, in a wrench of the type described, a pair of levers, one being longer than the other each lever having a head formed with a confronting rectilinear gripping edge, arranged at all times in parallelism no matter how far apart these gripping edges may be separated.

A further object of this invention is to provide a combination pipe and nut wrench in which a pair of levers are pivoted in superposed relationship for conjoint action, being pivoted in such a manner upon a handle that their jaw heads will always be maintained parallel in any adjusted position of the levers whereby the nut engaging notch made by both heads will function properly in any size produced by the swinging of both levers.

A still further object of this invention is to provide a pipe and nut wrench in which two levers are pivoted in a bifurcated portion of the handle, in such a manner that one lever projects in advance of the other, both levers having at their front confronting ends rectilinear heads with parallel rectilinear edges, said handle having an elongated groove in which slides a plunger carrying a dog for engagement with one lever to swing this lever, means being provided whereby both levers will move at the same time with their heads maintained in parallel relation.

The present invention also embodies a handle, in the slotted front end of which two levers, one longer than the other are pivoted in contacting superposed relation for joint action, the levers swinging against the tension of a spring, and providing spaced apart gripping jaws, with parallel gripping edges, the arrangement being such that the innermost lever is shouldered pivotally against an arcuate portion of the handle, so that all stresses impressed upon this lever or upon both levers will be counteracted by the handle directly.

With the above and other objects in view my invention consists in the combination, arrangement and details of construction disclosed in the drawing and specification, and then more particularly pointed out in the appended claim.

In the drawing, wherein similar reference char-

acters designate similar parts thruout the respective views,

Figure 1 is a side elevation of my invention,
Figure 2 is a longitudinal, fragmental sectional view thereof,

Figure 3 is a view similar to Figure 2 but showing the two jaws open further apart,

Figure 4 is a top plan view of the invention,
Figure 5 is a bottom plan view thereof,

Figure 6 is a front end elevation with the levers removed,

Figure 7 is a front end elevation with the long lever removed, and

Figure 8 is a front elevation of the wrench.

Referring to the drawing and specification, which are merely illustrative of my invention 10 designates a rigid handle for the nut and pipe wrench. The handle is bifurcated at its front end and is provided with two walls the front edges of which have central arcuate bosses or portions 14, 14' respectively, the slot between these walls being designated 11. The upper corner edges of the bifurcated portion are designated 12, being separated by recesses 13 from the bosses 14, 14'. A pin 15 is secured in both upper corners 80 12 and secured fixedly upon and around this pin is one end of a stout resilient member or sear spring 18 pressing against the adjacent longitudinal curved edge of a short lever 20, which at its outer end is pivoted upon a pin 17' also passing concentrically within the bosses 14, 14' of handle 10.

The front end of lever 20 is formed with opposing lateral shoulders 15a formed by means of the head 28 which is as wide as the handle 90 but wider than the lever 20 proper, this head having its outermost surface formed plane or flat. The shoulders 15a are arcuate in formation and contact swingingly the arcuate bosses 14, 14' of the handle as the lever 20 oscillates on pivot pin 95 17'.

There is also provided a longer lever 22 whose inner curved edge frictionally engages the adjacent edge of the short lever 20, lever 20 having a teat 21 fitting recess 23 in lever 22, while lever 100 22 has a similar teat 29 designed to fit into the notch or recess made or that may be made to receive the same in lever 20. The long lever 22 has an angular portion which projects in advance of the head 28 of lever 20 and it has 105 an inner angular edge 27 joining the serrated rectilinear or straight edge 26 the latter edge being disposed parallel to edge 28 of lever 20.

It will also be noted that the jaw 26 has its outer face curved or formed convex as at 25. 110

Both levers are thus mounted in superposed relation and normally there is a notch between the surface 26 of lever 22 and the surface 28 of lever 20, these edges being parallel so that a nut can easily fit into this recess and be gripped by the jaws when the handle 10 is swung in a counterclockwise direction.

The under edge of the handle 10 is formed with an elongated slot or groove 38, and disposed in parallel relation in this groove are a pair of fixed ears 33, and 32 formed upon the inner edge of this groove and slidably mounted in these ears is the plunger 37 the rear portion of which, located to the rear of ear 33, has an operating push handle 35 acting as a manually operated means to swing both levers 20 and 22.

There is a pin 40 on the plunger 37 bearing against one end of a coiled spring 36 wound around the plunger 37 and bearing against the ears 32, 33. The free end of the plunger 30 may be slightly curved and it has a shoulder or flange 31 bearing against ear 32 under normal condition of the spring 36. The terminal 30 of this plunger engages or bears against the inner end of the long lever 22. 16 designates the curved lower corners of the bifurcated portion of the handle.

It will now be seen that the terminal 30 and spring 18 straddle the outer edges of the levers 22 and 20 respectively. In the operation of the wrench the handle 35 is slid along in the handle 10 pin 40 moving to compress the coiled spring 36 as shown in Figure 3, the terminal 30 advancing far enough to tilt the long lever 22, which, bearing against the shorter lever 20 urges this short lever to tilt with it, so that both levers swing upon their pivots together. Long lever 22 is pivoted eccentrically with respect to lever 20 upon the pivot pin 17 secured in the bifurcated portion of the handle 10. When both jaws 26, and 28 with their parallel edges swing in unison with levers 20 and 22, urged on by plunger 30, then jaw 26 separates some distance apart from jaw 28, but these rectilinear edges are still maintained in correct parallel relation to one another, so a larger size nut may now be gripped between these jaws. When pressure is released from handle 35 the spring 36 will expand and the plunger will be restored to normal position shown in Figure 2.

A pipe or nut is thus adapted to be rigidly held between the vise-like jaws of the levers. Any

severe stress such as will be engendered in the act of turning a nut by the use of this wrench or turning a pipe held in the jaws, will be impressed thru the small lever 22 upon the arcuate bosses 14, 14' on the handle so that considerable strain will be removed from the pivot pins 17, or 17'. The two levers swing against the tension of the sear or leaf spring 18.

After the nut or pipe shall have been inserted between the jaws of the wrench the handle 10 will be swung counterclockwise so that the nut or pipe will hold the jaws against receding movement so now as the handle is turned the plunger 30 will force the two levers 20 and 22 to move so the nut may be screwed on or off its fitting or a pipe unscrewed or screwed from its rest or support.

I do not intend to limit myself to the exact details of construction save as pointed out in the appended claim.

What I desire to claim and seek protection on is as follows:—

A device as described consisting of a handle whose front terminal is bifurcated, the front edges of the sides of the bifurcated terminal being formed with parallel sector shaped anvils, a lever 10 projecting into said bifurcated portion of the handle and having a front T-head of a width corresponding with that of the handle, said T-head having an inner concave surface designed to pivotally ride in contact with the sector-shaped anvils in all positions, a pivot pin projecting through both anvils concentrically and into the lever to allow the latter to rock upon said anvils, a second lever made longer than the first and having an outer serrated jaw disposed in spaced parallel relation to the T-head and its inner end also projecting into the bifurcated terminal, resilient means pressing the inner ends of both levers together for joint movement, the inner end of the T-head engaging the inner face of the arm of the longer lever, manually operated means for swinging both levers jointly and for releasing them, and means for pivoting the longer lever between the points of contact of the inner ends of the two levers with each other and the points of contact of the inner end of the T-head and the inner face of the longer arm so that when both levers swing the serrated jaw and T-head remain parallel.
